HACK SAW

Raymond C. Dreier, Chicago, Ill., assignor to Dreier Brothers, Inc., Chicago, Ill., a corporation of Illinois

Application February 23, 1956, Serial No. 40,303

Term of patent 14 years

(Cl. D93—3)

Fig. 1 is a side elevational view of a hack saw embodying my new design;

Fig. 2 is a top plan view thereof;

Fig. 3 is a bottom view of the saw;

Fig. 4 is an end view of the saw as seen from the left of Fig. 1;

Fig. 5 is a view of the opposite end of the saw as seen from the right of Fig. 1;

Fig. 6 is a cross-sectional view taken substantially along 6-6 in Fig. 1; and

Fig. 7 is a cross-sectional view of the saw taken substantially along the line 7-7 in Fig. 1.

The essential features of my design reside in those portions shown in full lines.

I claim:

The ornamental design for a hack saw, substantially as shown and described.
